UNITED STATES PATENT OFFICE.

JOHN W. SEVERT, OF MABEN, WEST VIRGINIA.

DESIGN FOR A SETTEE-ROCKER.

48,329.

Specification for Design.

Patented Dec. 21, 1915.

Application filed August 20, 1915. Serial No. 46,565. Term of patent 14 years.

To all whom it may concern:

Be it known that I, JOHN W. SEVERT, a citizen of the United States, residing at Maben, in the county of Wyoming and State of West Virginia, have invented a new, original, and ornamental Design for Settee-Rockers, of which the following is a specification, reference being had to the accompanying drawing, forming part thereof.

The figure is a perspective view of the settee rocker, showing my new design.

I claim:

The ornamental design for a settee rocker, as shown.

JOHN W. SEVERT.

Witnesses:

H. C. ELLETT,
C. R. McNUTT.
